UNITED STATES PATENT OFFICE.

SAMUEL H. KELM, OF SALEM, ILLINOIS.

AIR-DRYING APPARATUS.

1,098,506.

Specification of Letters Patent.

Patented June 2, 1914.

Application filed June 2, 1913. Serial No. 771,196.

To all whom it may concern:

Be it known that I, SAMUEL H. KELM, a citizen of the United States of America, residing at Salem, in the county of Marion and State of Illinois, have invented certain new and useful Improvements in Air-Drying Apparatus, of which the following is a specification.

This invention relates to certain new and useful improvements in an apparatus to be used for drying air and removing therefrom all impurities or foreign substances, so that the air thus dried or purified may be conducted to any suitable point or device and be employed for any desired purpose; and it consists in certain peculiarities of the construction, novel arrangement and operation of the various parts thereof, as will be hereinafter more fully set forth and specifically claimed.

The principal object of the invention is to provide an air purifying apparatus, which shall be simple and inexpensive in construction, compact in form, strong, durable and efficient in operation, and so made that its parts may be easily assembled or readily detached and removed for cleansing and repairs when necessary.

A further object of the invention is to provide a distributer for the air, which shall be of such construction as to prevent any back pressure within the container of the apparatus, and which shall cause the air passing through the parts of the distributer to pursue circuitous routes or passages, and to be passed through drying and filtering material, to the end that when the air passes from the distributer it will be absolutely dry and free from foreign substances or impurities.

A further object of the invention is to provide automatic means for removing from the container or receptacle the condensation or water extracted from the air.

Other objects and advantages of the invention will be disclosed in the subjoined description and explanation.

In order to enable others skilled in the art to which the invention pertains to make and use the same, I will now proceed to describe it, referring to the accompanying drawing, in which—

Figure 1 is a central vertical sectional view of an air drying apparatus illustrating one form of my invention, the said section being taken on lines 1—1 of Figs. 2 and 3

of the drawing; Fig. 2 is a fragmental plan view of the apparatus shown in Fig. 1; Fig. 3 is a detached perspective view of the distributer embodying the construction illustrated in Fig. 1; Fig. 4 is a detached perspective view of another form of the distributer, and Fig. 5 is a plan view of the distributer shown in Fig. 3.

Like numerals of reference refer to corresponding parts throughout the different views of the drawing.

The reference numeral 6 designates the casing or container of my apparatus, which may be of any suitable size, form and material, but preferably of metal, and cylindrical in shape as shown in Figs. 1 and 2 of the drawing. The lower portion of the receptacle 6 is open and provided with an annular flange 7, to which is secured by means of bolts 8, a bottom or base 9, which tightly and securely closes the receptacle 6, at its lower end. This bottom or base is provided on its upper surface with a raised lug or boss 10, in the upper surface of which is formed a valve seat 11, from which leads an opening 12, which communicates with the cavity of a nipple 13, to which a drain pipe (not shown) may be connected. The boss 10, or raised portion of the base 9, is pro-

vided with an upright stud 14, to which is pivotally secured one end of a lever 15, to the other end of which lever is pivotally secured a rod 16, which supports a float 17, of any suitable size, form and material. Pivotally mounted on the lever 15, near its fulcrum point is a valve 18, which has its lower end formed to correspond with the shape of the valve seat 11, with which it is adapted to coöperate to open and close the outlet 12, through the bottom of the receptacle. Extended downwardly from the valve 18, through the opening 12, is a stem 19, which may have on its lower portion a nut 20, to restrict the upward movement of the said valve or the entire removal of the stem 19, except when desired. The upper end of the receptacle 6, is provided with a head 21, which has an opening 22, preferably located in the center thereof for the reception of the neck 23, of the air distributer. The head 21 is also provided with an opening 24, with which an outlet pipe 25, for the dried and purified air communicates, which pipe may lead to any desired point or device, so that such air can be used for any desired purpose. Connected to the neck 23, of the air

distributer is a pipe 26, which communicates at its other end with a supply of air (not shown) under pressure.

As is clearly shown in Figs. 1 and 3 of the drawing, the air distributer consists of a conduit 27, to which the neck 23, is secured or preferably made integral therewith as shown. The bore of the conduit 27 is by preference downwardly flared as illustrated in Fig. 1, so that as the air passes from the supply pipe 26, through the neck 23, and conduit 27, into the receptacle 6, it will expand and reduce or prevent too great pressure thereof within the lower portion of the receptacle. The lower portion of the conduit 27, is provided with an external annular flange or floor 28, and at a suitable distance above said flange or floor the conduit 27 is provided with another external annular flange 29, which flanges are of sufficient size to fit snugly the cavity of the receptacle 6, in the upper portion of which the distributer is located. Between the flanges 28 and 29 are located a number of upright partitions usually four in number, but I wish it understood that I do not limit myself to such number as I may employ a greater or less number of said partitions. As there are only four of these partitions shown in the present construction, they will be designated by the numerals 30, 31, 32 and 33, and as shown are radially extended from the conduit 27 to the peripheries of the flanges 28 and 29, which they unite so as to form several compartments, which compartments are designated by the numerals 34, 35, 36 and 37. These compartments are arranged and constructed so that each alternate one will have passages for the admission of air thereto through the flange 28, and for the outlet of air through the flange 29. In other words, the air is admitted to one of the compartments through its lower portion and then passes into the adjacent compartment, and from thence out through the upper portion of the latter. To accomplish this the floor or flange 28 of one of the compartments, say the compartment 34, is provided with a series of perforations 38, and the flange 29, in its portion overlying the compartment 35, is provided with a series of perforations 39, for the outlet of air. As shown the segments or sections of the flange 29, covering the compartments 34 and 36 are provided with cavities 40, the lower surface or wall of which is furnished with a series of perforations 41, which lead from the compartment 34, to said cavity. This cavity communicates with the compartment 35, by means of a channel 42, formed in the partition 31, which channel also communicates with a cavity 43, formed in the section of the flange 28, which forms the floor of the last named compartment. The cavity 43, communicates with the compartment 35, by means of a series of perforations 44 which

are formed in the upper wall of said cavity. The same arrangement and construction is carried out in the compartments 36 and 37, and if more than four compartments should be employed the same construction would be employed in alternate compartments. 70

In Fig. 4 of the drawing is shown another way of constructing the air distributer, which acts on the same principle as that shown in Figs. 1, 3 and 5, and just above described, except that the paths or passageways through which the air must travel is not as circuitous as in the former construction. In the construction now under consideration, the distributer as in the other construction consists of a conduit 27, having a neck 23, and provided with horizontal flanges 28^a and 29^a located at suitable distances apart, one above the other, the space between said flanges being divided into compartments by means of a number of radial partitions usually four in number, two of which only 30^a and 31^a are shown in the drawing. These partitions are alternately provided with an opening 45, so that the air passing upwardly into one of the compartments can pass through said opening into the adjacent compartment, and then outwardly through the top of the last named compartment, and so on throughout the series of 95 compartments. For this purpose the floor or bottom of each alternate compartment is provided with perforations 46, and the top or roof of each alternate compartment is provided with perforations 47, of any suitable size and number, but in this construction, as well as in the construction shown in Figs. 1, 3 and 5 of the drawing, it is preferred to have the area represented by the perforations in the floors of the compartments and the perforations in the top or ceilings of said compartments equal in area to each other, and equal in area to the inlet and outlet each of the distributer, in order that there will be a free circulation of air 100 without any back pressure in the lower portion of the receptacle 6 or container. 105

From the foregoing and by reference to the drawing, it will be readily understood and clearly seen that by admitting air to the 115 receptacle 6, through the inlet or supply pipe 26, neck 23, and conduit 27, it will pass into the lower portion of said receptacle and thence upwardly through the openings in the lower flange of the distributer or 120 floors of the alternate compartments of the distributer, which compartments are supplied with absorbent or drying material, such as sea moss 48, or other suitable fibrous absorbing and straining substance. From 125 said compartments, when the distributer is constructed as shown in Figs. 1, 3 and 5, the air will pass through the openings 41, in the lower walls of the cavities 40, into said cavities, and from thence through the chan- 130

nels 42, into the cavities 43, and from thence through the openings 44, in the compartments adjacent to the first named compartments, and from thence out through the 5 openings 39, into the dry air chamber 49, from which it will be conducted through the outlet pipe 25, to the point of consumption or use. When the construction of the distributor illustrated in Fig. 4 is employed, 10 virtually the same operation takes place, except that instead of the air passing through the cavities 40, and 43, and channels 42, it will pass from one compartment through the opening 45, into the adjacent 15 compartment, and from thence through openings 47, in the top of the distributor and into the drying chamber, and from thence out through the outlet pipe. It will be understood that each of the compartments 20 of the distributor is supplied with sea moss, or its equivalent, but for the sake of clearness in the drawings the illustration of this material has been omitted from most of said compartments.

25 As there will be considerable air pressure within the receptacle and downwardly against the float 17, the latter is mounted on one end of the lever 15, which is fulcrumed at its other end and carries near its 30 fulcrum, the valve 18, which controls the outlet for the condensation or water extracted from the air. By this arrangement, the leverage afforded to the float will neutralize the action of the air pressure, so that the 35 float and valve may be raised by a small quantity of water, to the end, that some of the latter may pass out through the opening 12, after which the valve 18 will be automatically seated. By forming the valve 40 seat 11, in the raised portion 10, of the bottom of the receptacle, it is apparent the impurities removed from the air, and scales and the like falling from the walls of the receptacle and distributor will settle on the 45 bottom of the latter without getting into the valve seat or interfering with the operation of said valve.

While I have shown and described the air drying apparatus in its preferred embodiment, yet I do not wish to be understood as limiting myself to the exact construction, as various changes therein may be made without departing from the scope of the appended claims.

55 Having thus fully described my invention what I claim as new and desire to secure by Letters Patent, is—

1. In an air drying apparatus, the combination with a receptacle having an inlet and 60 an outlet for air, of an air distributor in said receptacle and communicating with said inlet and consisting of a conduit, a pair of spaced apart flanges, a series of partitions between said flanges dividing the space 65 therebetween into compartments, air drying

material in said compartments, said compartments having alternately passages for the inlet and outlet of air at their lower and upper parts respectively and in communication with one another.

2. In an air drying apparatus, the combination with a receptacle having an inlet and an outlet for air, of an air distributor in said receptacle in communication with said inlet and consisting of a conduit, a pair of spaced apart flanges, a series of partitions between said flanges dividing the space therebetween into compartments, air drying material in said compartments, said compartments having alternately passages for the inlet and outlet of air at their lower and upper parts respectively and in communication with one another, the aggregate area of said passages being the same as the area of the inlet and the same as the area 70 of the outlet for the air.

3. In an air drying apparatus, the combination with a receptacle having an inlet and an outlet for air in its upper portion and an outlet for water in its lower part, of an automatic valve controlling said water outlet, an air distributor in said receptacle in communication with said inlet and consisting of a conduit, a pair of spaced apart flanges, a series of partitions between said flanges dividing the space therebetween into compartments, air drying material in said compartments, said compartments having alternately passages for the inlet and outlet of air at their lower and upper parts respectively and in communication with one 75 another.

4. In an air drying apparatus, the combination with a receptacle having an inlet and an outlet for air in its upper portion and an outlet for water in its lower part, of a float controlled valve for said water outlet, an air distributor in said receptacle in communication with said inlet and consisting of a conduit, a pair of spaced apart flanges, a series of partitions between said flanges dividing the space therebetween into compartments, air drying material in said compartments, said compartments having alternately passages for the inlet and outlet of air at their lower and upper parts respectively and in communication with one 80 another.

5. In an air drying apparatus, the combination with a receptacle having an inlet and an outlet for air in its upper portion and an outlet for water in its lower part, of an automatic valve controlling said water outlet, an air distributor in said receptacle in communication with said inlet and consisting of a conduit, a pair of spaced apart flanges, a series of partitions between said flanges dividing the space therebetween into compartments, air drying material in said compartments, the said flanges having cavi- 85 90 95 100 105 110 115 120 125 130

ties located alternately at the top and bottom of the alternate compartments said cavities having communication with one another through a channel formed in the partition dividing said compartments and also having openings in their inner walls.

6. In an air drying apparatus, the combination with a receptacle having an inlet and an outlet for air, of an air distributor in 10 said receptacle and communicating with said inlet and consisting of a conduit, a pair of spaced apart flanges, a series of partitions between said flanges dividing the space therebetween into compartments and each 15 alternate partition having passageways affording communication between the compartments in pairs, air drying material in said compartments, said compartments hav-

ing alternately passages for the inlet and outlet of air at their lower and upper parts 20 respectively.

7. An air distributer for air drying apparatus consisting of a conduit, a pair of spaced apart flanges, a series of partitions between said flanges dividing the space 25 therebetween into compartments, air drying material in said compartments, said compartments having alternately passages for the inlet and outlet of air at their lower and upper parts respectively and in communication with one another. 30
